UNITED STATES PATENT OFFICE.

JULIUS H. SCHLAFLY, OF CANTON, OHIO, ASSIGNOR TO THE CANTON CULVERT COMPANY, OF CANTON, OHIO, A CORPORATION OF OHIO.

DRAINING-CULVERT.

980,442.

Specification of Letters Patent. Patented Jan. 3, 1911.

Application filed January 4, 1910. Serial No. 536,395.

To all whom it may concern:

Be it known that I, JULIUS H. SCHLAFLY, a citizen of the United States, residing at Canton, in the county of Stark and State of Ohio, have invented a new and useful Draining-Culvert, of which the following is a specification.

My invention relates to improvements in the construction of sheet metal culverts of the sectional, nestable type adapted not only to conduct water from place to place but to drain water from the soil surrounding the culvert, and the object of my improvement is to provide a device of the character mentioned which will be simple, cheaply constructed, strong and durable and well adapted to the purpose for which it is intended. I attain this object, and other objects readily apparent to those skilled in the art, by the construction illustrated in the accompanying drawing, in which—

Figure 1 is a perspective view of a draining culvert embodying my invented improvements, a portion of the flange on the lower section being broken away. Fig. 2 is a top view of one of the upper sections. Fig. 3 is a transverse sectional view through that portion of the culvert where longitudinally adjacent upper sections over-lap. Fig. 4 is a side elevation illustrating two upper sections and a lower section properly connected together and the flange of the lower section broken away to disclose the construction.

Throughout the several views similar numerals of reference indicate similar parts.

The numeral 1 indicates a bottom section, preferably formed with a plain, flat upper surface and having side or retaining flanges 2 along both longitudinal edges. The numeral 3 indicates one of the upper sections while 3^a indicates a similar section longitudinally adjacent to the section 3. Each upper section is preferably arched or curved and is provided along its longitudinal edges with the integral flanges 4. Circumferential corrugations extend from the outer edge of the flange on one side to the outer edge of

the flange on the other side, the corrugations 50 extending not only throughout the arched portion of the section but through the flanges 4. The purpose of the corrugations in the arched portion of the culvert is to strengthen the same and enable it to withstand the crushing pressure of the earth immediately above it, while the corrugations in the flanges 4 strengthen said flanges and provide a broad bearing to support the arched portion, the said flanges having less 55 tendency to bend along the line of their attachment to the arched portion and in fact throughout their width by reason of the strengthening corrugations, and thus distribute the weight or pressure over a substantially larger surface. A further purpose 60 of the circumferential corrugations is to conduct water to the draining apertures, as 65 hereinafter described.

In erecting the culvert longitudinally adjacent upper sections are over-lapped at their meeting ends one full corrugation, as illustrated in Figs. 1 and 4 and bolts 5 or their equivalents are used for the purpose of connecting the upper sections to the lower sections. The apertures 6 in the flanges 4 are elongated transversely with respect to the culvert for the purpose of permitting adjustment of the upper sections relative to the lower sections so as to bring the edges of the flanges 4 against the flanges of the lower sections as illustrated in Fig. 3 and also to permit of some slight adjustment of the upper and lower sections when either surrounding ground or water within the culvert itself 70 is frozen.

In the arched portion of each upper section are arranged a number of draining apertures 7, which apertures are preferably located in the externally concave surfaces 75 formed by the circumferential corrugations to increase the draining efficiency. When water has percolated through the soil and come into contact with the surface of one of the upper sections it will be directed along 80 said surface into the nearest concave corrugation, whence it will flow circumferentially 85 along the side of the section to the first aper-

ture in its pathway and through said aperture into the interior of the culvert. In placing culverts of the character herein described it is desirable to provide a firm and smooth foundation for the lower section and to fill in around the top section a quantity of coarse gravel or broken stone to aid in the rapid draining of water from the surrounding soil to the surface of the upper sections, whence it will be carried into the interior of the culvert as just described.

It will be noted that while my draining culvert may be used to advantage in practically all places where an ordinary culvert might be used, yet it is especially designed for draining fills on railways or in other places where it is desired to combine a means for conducting water with a means for draining the surrounding ground.

20 The culverts may be shipped in a knocked-down and nested condition and a culvert of any desired length may be formed by connecting up the necessary number of sections. Both upper and lower sections may be made in any desired or convenient length, joints between longitudinally adjacent upper sections being preferably arranged intermediate joints between longitudinally adjacent lower sections.

30 It will be noted that by reason of the transverse corrugations in the flanges 4 the said flanges do not lie flat against the lower section but contact with said section only where the corrugations in said flanges are convex on the underside, as clearly illustrated in Fig. 4. Intermediate each two points of contact is an air space 8 produced by the upwardly convex corrugation, said air space permitting the rapid drying of 40 water from between the contacting surfaces of the flanges 4 and the lower section and thus to a large extent preventing the rapid corrosion or rusting of the metal. Attention should also be called to the fact that a certain amount of water will enter the culvert 45 by coming in contact with the upper surface of the flanges 4, following said surface to the edge of the flange and seeping downwardly between the flange 2 and the edge 50 of the flange 4; whence it will be readily conducted under the flange 4 to the interior of the culvert through the spaces 8.

While I have illustrated and described the upper sections as arched I do not desire to 55 be confined to that construction as it is evident that said sections might be formed of an inverted V-shape or otherwise and also other minor changes of form or detail might be made without departing from the spirit 60 of the invention.

I claim:—

1. A sheet metal culvert section provided

with circumferential corrugations and with draining apertures, substantially as and for the purpose specified.

2. A culvert section provided with circumferential corrugations presenting externally convex and concave portions, and draining apertures in the said concave portions.

3. A sheet metal culvert section provided with transverse corrugations presenting externally concave and convex portions and apertures located in the concave portions.

4. As an article of manufacture, a culvert 75 section constructed of sheet metal, bent into arched form, and having draining apertures in its wall.

5. As an article of manufacture, a culvert 80 section constructed of sheet metal, bent into arched form, having circumferential corrugations, and draining apertures in the wall of said section.

6. As an article of manufacture, a culvert 85 section constructed of sheet metal bent into arched form, having circumferential corrugations, and draining apertures extending through the wall of said section, said apertures being located in the externally concave portions of the section.

7. An arched culvert section provided with integral flanges at its lateral edges, circumferential corrugations extending through said flanges, and draining apertures in the wall of the arched portion of the section.

8. An arched culvert section provided with integral flanges at its lateral edges, circumferential corrugations extending through said flanges, and draining apertures in the wall of the arched portion of the section, 100 said apertures being located in the externally concave portions of the corrugations.

9. In a culvert of the class described, a longitudinal series of sections adapted to be lapped longitudinally one upon the other at 105 their meeting edges, and draining apertures in the walls of said sections.

10. In a culvert of the class described, a series of transversely corrugated sections adapted to be lapped longitudinally one upon the other at their meeting edges, said sections having apertures located in the externally concave portions of their walls.

11. A sheet metal culvert comprising an upper and a lower section, the upper section bent into arched form and having draining apertures in its wall, the lower section provided with a plain upper surface and side flanges along its longitudinal edges, and the said upper section arranged upon said lower 120 section between the side flanges thereof.

12. A sheet metal culvert comprising an upper and a lower section, the upper section bent into arched form, provided with circum-

ferential corrugations, and having draining apertures in its wall, the lower section provided with a plain upper surface and side flanges along its longitudinal edges, and the said upper section arranged upon said lower section between the side flanges thereof.

13. A sheet metal culvert comprising an upper and a lower section, the upper section bent into arched form, provided with circumferential corrugations, and lateral flanges, and having draining apertures in its wall, the lower section provided with a plain upper surface and side flanges along both longitudinal edges, and the said upper section arranged upon said lower section between the side flanges thereof.

14. A sheet metal culvert comprising an upper and a lower section, the upper section bent into arched form, provided with circumferential corrugations, and having draining apertures in its wall, said apertures located in the externally concave portions of the corrugations, the lower section provided with a plain upper surface and having side flanges along its longitudinal edges, and the said upper section arranged upon said lower section between the side flanges thereof.

30 15. A sheet metal culvert comprising an upper and a lower section, the upper section bent into arched form and provided with circumferential corrugations and integral lateral flanges, the circumferential corrugations extending through said flanges, said upper section having draining apertures in its wall, the lower section provided with a plain upper surface and side flanges and the upper section arranged upon the lower section between the side flanges thereof.

45 16. A sheet metal culvert comprising an upper and a lower section, the upper section bent into arched form and provided with circumferential corrugations and integral lateral flanges, the circumferential corrugations extending through said flanges, said upper section having draining apertures in its wall, said apertures located in the externally concave portions of the corrugations, the lower section provided with a plain upper surface and side flanges, and the said upper section arranged upon said lower section between the side flanges thereof.

55 17. A culvert comprising an upper and a lower section, the upper section provided with lateral, corrugated flanges, and the upper section arranged upon said lower section, said corrugated flanges resting upon the plain upper surface of said lower section.

60 18. In a culvert two sheet metal sections joined to each other, one of said sections provided with a corrugated flange and the other

section provided with a plain surface, and the corrugated flange of the one section resting upon the plain surface of the other 65 section, whereby air spaces are produced adjacent the contacting portions of the two sections.

19. A culvert comprising an upper arched section and a lower plain section, the upper arched section provided with lateral corrugated flanges adapted to rest upon the plain upper surface of said lower section, and means for fastening said sections together. 75

20. A sheet metal culvert comprising an upper and a lower section, the upper section provided with an arched portion and integral lateral flanges, circumferential corrugations extending through said flanges 80 and arched portion, said arched portion provided with draining apertures located in the externally concave portions of the corrugations, and said upper section arranged upon said lower section with the corrugated 85 flanges of said upper section resting upon plain portions of said lower section.

21. A culvert comprising an upper section having an arched portion and integral lateral flanges extending outwardly from 90 the bases of said arched portion, a lower plain section extending under said lateral flanges and said flanges resting upon said lower section.

22. A culvert comprising an upper section having an arched portion and integral lateral flanges extending outwardly from the bases of said arched portion, said upper section provided with transverse corrugations extending through said arched portion and the integral flanges, a lower plain section 100 extending under said lateral flanges and said flanges resting upon said lower section. 95

23. A culvert comprising an upper section having an arched, circumferentially corrugated portion, and integral lateral flanges extending outwardly from the bases of said arched portion, a lower plain section extending under said lateral flanges and said flanges resting upon said lower section. 105 110

24. A sheet metal culvert comprising upper sections provided with draining apertures and lower sections provided with plain upper surfaces, said upper sections arranged upon said lower sections. 115

25. In a culvert a longitudinal series of upper sections provided with draining apertures and a longitudinal series of lower sections, said upper series of sections arranged upon said lower series of sections. 120

26. In a culvert a longitudinal series of upper sections provided with draining apertures and a longitudinal series of lower sections provided with plain upper surfaces,

said upper series of sections arranged upon said lower series of sections.

27. A sheet metal culvert comprising an upper and a lower section, the upper section bent into arched form and provided with lateral flanges, the lower section provided with a plain upper surface and side flanges along its longitudinal edges, and the upper section arranged upon said lower section between the side flanges thereof, with

the lateral flanges of the upper section resting upon the plain upper surface of the lower section.

In testimony that I claim the above, I have hereunto subscribed my name in the 15 presence of two witnesses.

JULIUS H. SCHLAFLY.
